UNITED STATES PATENT OFFICE

JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

SLIDE BUCKLE

Application filed April 4, 1930. Serial No. 441,671.

This invention relates to slide buckles employed for adjusting the length of straps, webbing, and the like upon which the buckle is mounted, the adjustment being maintained thereby without any penetration into the material, and the objects of the invention are to provide an entirely rigid and indestructible slide buckle; to provide a slide buckle that is reversible; to provide a wire slide buckle of integral outer and inner rectangular frames having a common plane; to provide such a structure of which the outer frame provides upper and lower parallel bars and of which the inner frame provides relatively spaced bars extending across the buckle in spaced relation to the outer and inner bars, respectively; and to provide such an outer and inner frame structure of which the metal of the respective terminals are united in permanent intimate union with engaging metal of the frames. With these and other objects in view as may become apparent from the within disclosures, the invention consists not only of the particular form herein pointed out and illustrated in the drawing, but readily admits of certain modifications within the scope of what hereinafter may be claimed.

The character of the improvement may be best understood by reference to one illustrative device embodying the invention and illustrated by the accompanying drawing in which the Figure 1 is an elevation of the buckle of which the reversed elevation would be identical; and the Figure 2 is a top view thereof, the Figure 3 being an elevation of a modified form of buckle.

Referring more particularly to the drawing the buckle is made from a single piece of wire of which a middle portion is bent to form an outer rectangular frame having the upper bar 1 and the lower bar 2 integrally connected by the side bar 3, the opposite side of the outer frame being formed by the engaging looped structure terminals 4 and 5 provided by bending each wire portion within the frame and back upon itself, the remaining wire portions being bent relatively spaced and in spaced parallel relation to the upper and lower bars 1 and 2, respectively, to provide the intermediate bars 6 and 7 ex-

tending relatively spaced across the buckle, the wire terminals 8 and 9 being bent into relative longitudinal alignment within the frame adjacent the side bar 3 to complete the inner frame. The looped terminals 4 and 5 and the aligned wire terminals 8 and 9, respectively, are united in permanent intimate union by means of welding, brazing, or soldering, as at 10 and 11. The structure above described, and illustrated by the Figures 1 and 2, differs from the structure described and illustrated by the same applicant in an application filed December 13, 1929, Serial Number 413,864, in that there is there disclosed a slide buckle comprising a pair of loops in a common plane and having intermediate bars in relatively close association, while the present application discloses a structure of inner and outer frames arranged within a common plane, the inner frame providing the relatively spaced intermediate bars. The bars 6 and 7 may be of more or less distance apart, but their spaced relation to the bars 1 and 2, respectively, approximately as illustrated, is better adapted to offset a strap (not illustrated), intended to be threaded into the buckle in the usual manner; than if the bars 6 and 7 were relatively spaced, for instance, a thirty-second of an inch apart. The buckle is reversible in use in that the elevation reversed to that illustrated is identical therewith.

The structure illustrated by the Figure 3 is slightly modified in that, while outer and inner frames are provided in a common plane by bending a single length of wire, yet they are formed by doubling the wire and then bending the doubled wire in its own plane to assume rectangular forms, one within the other, and providing the relatively spaced parallel bars 1A and 6A, the relatively spaced parallel bars 2A and 7A, and the closely associated side bars 4A and 5A of one side of the frames and the wire terminals 3A and 9A forming the other side. The extremities of the wire terminals 3A and 9A being united in permanent intimate union with engaging portions of the frames, as at 10A, the meeting metal surfaces of the bars 4A and 5A being likewise united, as at 11A.

I claim:

1. A slide buckle comprising a piece of wire of which a middle portion is bent to form a rectangular frame having upper and lower bars integrally connected by a side bar, portions of the wire, aligned one with the other, cooperating to form the opposite side of the frame, each aligned portion being bent back upon itself within the frame, and the remaining wire portions being bent to extend in the plane of the frame and spaced one from the other and from the upper and lower bars, respectively, to the integrally connecting side bar, the wire extremities being bent into longitudinal alignment, one with the other, within said plane, and the engaging metal of the extremities and of the side portions, respectively, being united in permanent intimate union to provide a rigid structure wholly within said plane.
2. A slide buckle comprising a piece of wire of which a portion is bent to form a rectangular frame having upper and lower parallel bars, other integral portions of the wire being bent to provide intermediate bars spaced one from the other and from the upper and lower bars, respectively, the metal of the structure and wire terminals each being united in permanent intimate union with the engaging metal of the frame to provide a rigid structure.
3. A slide buckle comprising a piece of wire of which a middle portion is bent to form an outer rectangular frame having upper and lower bars integrally connected by a side bar, portions of the wire, aligned one with the other, cooperating to form the opposite side of the frame, each aligned portion being bent back upon itself within the frame to be further bent to form an inner frame within the plane of the outer frame, the upper and lower bars of the inner frame providing intermediate bars spaced one from the other and from the upper and lower bars of the outer frame, and the metal of the structural and wire terminals, respectively, being united in permanent intimate union with the engaging metal of the frames to provide a rigid structure.

50 JOHN H. DOMKEE.
